CATALYTIC CONVERSION OF
HYDROCARBONS

Forrest H. Blanding, Elizabeth, N. J., assignor to
Standard Oil Development Company, a corpora-
tion of Delaware

Application June 20, 1947, Serial No. 755,909

2 Claims. (Cl. 196—49)

1

This invention relates to the catalytic cracking of hydrocarbons.

In the cracking of hydrocarbons it has now been found that when cracking gas oils in the presence of synthetic silica alumina gel catalyst, there is a difference in the octane number of the gasoline produced when using high boiling gas oil and low boiling gas oil. When cracking a high boiling gas oil the gasoline produced has a substantially lower octane number than when cracking a low boiling gas oil.

When cracking high boiling gas oils with acid treated clay catalysts the octane number of the gasoline produced is also lower than with the low boiling gas oil but the difference is not as great as when using the synthetic catalyst.

It has been found that there is a very definite feed stock boiling level at which the octane number of the gasoline obtained when cracking gas oils with synthetic silica alumina catalyst changes markedly. For example, when cracking a certain narrow boiling feed stock with an average boiling level of 500° F. at certain fixed operating conditions and conversion level, a 95 octane number (CFR Research) gasoline is obtained. The average boiling level of a feed stock from the same crude oil source can be varied from about 450 to 750° F. and at similar operating conditions and conversion levels the gasoline produced will have octane numbers varying only about 0.1 to 0.3 number.

On the other hand if the average boiling level of the feed stock is further increased slightly to about 850° F. an abrupt drop of 5 octane numbers, to 90 octane number gasoline, will be obtained. The abrupt transition in octane level obtained is an unexpected and unusual phenomenon.

It has been found that when cracking similar gas oils with natural clay cracking catalysts, such as acid treated bentonites, that a much smaller change in octane level is obtained when the average feed stock boiling level varies between about 750° F. and 850° F. Thus, where with the use of synthetic silica alumina catalyst a gasoline of almost 3 octane numbers higher is obtained than with the acid treated clay or bentonite catalyst from a 600° F. average boiling point feed, a 0.4 higher octane number gasoline is obtained with the clay catalyst than with the synthetic catalyst for an 850° F. average boiling point feed.

It has thus been indicated that there is some particularly undesirable constituent in gas oils boiling above 800° F. which is harmful to the octane number of the gasoline produced from this gas oil, and that this material is relatively less harmful when cracking with a natural clay catalyst.

From the above it will be apparent that even though the synthetic catalyst is more expensive

5 than clay catalyst there is an advantage for using it on feed stocks boiling below about 800° F. due in part to the octane advantage. The synthetic and clay catalysts are closely competitive economically and if the octane advantage for the synthetic catalyst is removed, clay has the advantage of lower cost. As the acid treated clay catalyst gives better octane number gasoline for feed stocks boiling above about 800° F., an economical advantage will be obtained on the basis of octane credit by cracking feed stocks boiling below about 800° F. with synthetic catalyst and cracking feed stocks boiling above about 800° F. with the clay catalyst.

15 Furthermore, by using the lower boiling and relatively clean feed stocks with synthetic catalyst there will be less contamination of this more expensive catalyst, whereas, the cheaper natural catalyst may be used at a higher replacement rate 20 for the more contaminated higher boiling feed stocks.

According to one form of my invention, then, a 25 relatively narrow boiling feed stock boiling between about 430° F. and 800° F. and having an 80%—20% distillation temperature range¹ preferably of not more than about 200° F. is cracked over a synthetic silica alumina catalyst to give high octane gasoline and the fraction boiling above about 800° F., either narrow boiling or wide boiling, is cracked in a separate reactor or unit over a natural catalyst or other relatively cheap catalyst to produce as high or a higher octane gasoline product than is produced in cracking the narrow boiling stock above described.

30 According to another form of my invention gas oils are carefully fractionated to eliminate material boiling above about 800° F. when the gas oil is feed stock to a catalytic cracking unit employing the synthetic catalyst.

35 According to another form of my invention gas oils are carefully fractionated to eliminate material boiling above about 800° F. when the gas oil is feed stock to a catalytic cracking unit employing the synthetic catalyst.

40 With the use of my invention there should result substantially better overall product per unit operating cost in certain refinery situations.

In the drawing:

45 The figure represents one form of apparatus which may be used in carrying out my invention.

Referring now to the drawing the reference character 10 designates a fractionating tower into which hydrocarbon feed is introduced through line 12. The hydrocarbon feed stock may comprise a wide cut gas oil, crude petroleum oil, a reduced crude petroleum oil or other suitable hydrocarbon stock which is to be treated. In the fractionating tower 10 the hydrocarbon feed is fractionated into a bottoms fraction withdrawn through line 14, a gas oil fraction withdrawn as

¹ Calculated by subtracting the temperature in °F. at which 20% of the fraction distills off from the temperature in °F. at which 80% of the fraction distills off.

a side stream through line 16 and overhead vapors withdrawn through line 18.

Preferably the hydrocarbon oil being introduced into fractionating tower 10 is vaporized before it is introduced into the tower and if desired heating means may also be provided in the bottom of the fractionating tower. The vapors passing upwardly are fractionated as above set forth. The overhead vapors are passed through a condenser 22 for condensing normally liquid hydrocarbons and the cooled mixture is introduced into a separator 24 for separating gases from liquid hydrocarbons. The gaseous hydrocarbons pass overhead through line 26 and may be further treated for the recovery of normally liquid hydrocarbons or they may be utilized as such. The liquid hydrocarbons containing gasoline constituents are withdrawn through line 28 and passed to storage. Preferably a portion of the liquid hydrocarbons are passed through line 32 by pump 34 into the upper portion of the fractionating tower 10 as reflux liquid.

According to my invention I have found that improved octane number gasoline may be obtained by eliminating high boiling constituents from gas oil feed which is to be catalytically cracked. The gas oil fraction which is withdrawn from trap-out tray 36 from the tower 10 and through line 16 and in one case has an initial boiling point of about 430° F. and a final boiling point of about 800° F. The average boiling point of this feed stock is about 625° F. The average boiling point of the feed stock is obtained as the average of the temperatures at which 20% and 80% respectively, of the feed stock is distilled over in a batch distillation still having a distillation efficiency as good as or better than the equivalent of 15 plates operated at 5/1 reflux ratio.

The lower boiling feed stock comprising the gas oil withdrawn through line 16 is catalytically cracked in one vessel or reactor and the higher boiling fraction withdrawn through line 14 from the bottom of the fractionating tower 10 is catalytically cracked in a second vessel or reactor. The cracking of the lower boiling gas oil fraction will be first described.

The gas oil fraction withdrawn through line 16 may be vaporized and the vapors introduced into cylindrical reactor 38. Instead of vaporizing the gas oil fraction it may be partly preheated by heat exchange in the process and the partly preheated oil then mixed with a sufficient amount of hot regenerated catalyst from line 42 to vaporize the feed and raise it to cracking temperature. The catalyst to oil ratio in fluid catalytic cracking may vary between about one part of catalyst to one part of oil to 40 parts of catalyst to one part of oil by weight.

In the form of the invention shown in Fig. 1 the gas oil and hot regenerated catalyst are introduced into line 44 and passed into an inverted cone feed member 46 provided in its upper portion with a perforated distribution member or grid member 48 arranged in the bottom portion of the reactor vessel 38. Preferably the grid member 48 is circular and arranged concentrically with the vessel 38 in the lower portion thereof. The grid member 48 acts to evenly distribute the powdered catalyst and the oil vapors across the area of the reactor vessel 38. Instead of adding the catalyst particles and hydrocarbon feed together as a mixture the catalyst and hydrocarbon feed may be separately introduced into the vessel 38.

The temperature during the cracking of hydrocarbons may range from about 750° F. to 1050° F. and preferably about 925° F. to 1000° F. in the catalytic cracking of hydrocarbons to form high anti-knock gasoline. The catalyst to be used in cracking the lower boiling gas oil fraction comprises a synthetically prepared silica alumina gel.

The catalyst is preferably in finely divided form having a particle size between about 200 and 400 standard mesh and containing less than about 30% by weight of material smaller than about 20 microns. The temperature of the hot regenerated particles in line 42 is about 900° F. to 1100° F.

Returning now to the reaction vessel 38 the hydrocarbon feed and catalyst particles are introduced into the vessel 38 and the superficial velocity of the upflowing vapors is selected to maintain the solid particles in a dense dry fluidized liquid-simulating turbulent condition as shown at 52 and having a level as indicated at 54. The superficial velocity is that velocity measured with the vessel empty and may be between about 0.5 feet per second to 2.0 feet per second. Under these conditions and using the 200 to 400 mesh synthetic silica alumina catalyst material above described the density of the fluidized mixture in the reactor 38 may vary between about 15 pounds per cubic foot and 35 pounds per cubic foot.

Above the dense mixture is a dilute phase or dilute suspension 56 comprising vaporous reaction products containing some entrained catalyst particles. The upper portion of the reaction vessel 38 designated by the reference character 56 comprises a settling section in which the catalyst particles fall back into the dense mixture 52 so that only a dilute suspension or dispersed phase 56 is superimposed above the dense mixture 52. The density of the dilute suspension in the space 56 may vary between about .005 pound per cubic foot to 1 pound per cubic foot when using the silica alumina catalyst above referred to.

The vaporous reaction products containing some entrained catalyst particles leave the dilute phase section 56 and are passed into separation means 58 through inlet line 62 for removing or separating most of the solid particles from the vaporous reaction products leaving the space 56. The separation means is shown as a cyclone separator arranged in the upper portion of the reaction vessel 38 but other forms of separation devices may be used as for example Multiclones. If desired more than one separating stage may be used in series. It is not essential that the separating means 58 be inside the reaction vessel 38 as the separating means may be arranged outside of the reactor 38.

The separated solid particles collect in the separation means 58 and are returned to the dense bed or mixture 52 through dip pipe 64. The vaporous reaction products substantially free of catalyst particles pass overhead through line 66 and are introduced into the lower portion of a second fractionating tower 68. The fractionation of these vaporous reaction products will be presently described in greater detail.

During the reaction in the reaction vessel 38 the catalyst particles become contaminated or partly deactivated by the deposition of coke or hydrogen-containing carbonaceous material thereon. The catalyst particles are removed from the bottom portion of the reaction vessel 38 as a dense fluidized mixture and passed into 75 an annular stripping section 72 arranged below

the distribution grid member 48 and between the conical inlet member 46 and the inner wall of the reaction vessel 38. The partially spent catalyst particles are at a temperature of about 750° F. to 1050° F.

Stripping gas such as steam is introduced into the bottom portion of the stripping zone 72 through one or more lines 74 for removing hydrocarbon vapors entrained with the withdrawn spent catalyst. The superficial velocity of the stripping gas in the stripping zone is about 0.3 foot per second to 2 feet per second. The density of the fluidized mixture in the stripping zone 72 is about the same as the density of the dense mixture in the vessel 38 but it may be higher or lower.

In order to maintain the catalyst particles in a fluidized condition as they are withdrawn from the vessel 38, fluidizing gas is introduced through one or more lines 76 into the dense mixture in the bottom of the vessel 38. The dense fluidized and stripped catalyst particles are passed into a standpipe 78 having a control valve 82 for controlling the rate of withdrawal of catalyst particles from the reaction vessel 38.

The fluidized solids in the reaction vessel 38 and in the standpipe 78 produce a hydrostatic pressure at the base of the standpipe 78 which is used for passing the catalyst particles through the system. The spent particles leaving the standpipe 78 are mixed with a regenerating gas such as air or other oxygen-containing gas introduced through line 84 to make a less dense mixture or suspension and this suspension is passed through a regeneration zone diagrammatically shown at 86. The regenerated catalyst particles at a regeneration temperature are withdrawn and passed through line 42 and introduced into the reaction vessel 38 as above described. The hot regeneration gases are withdrawn through line 88.

While I have shown the regeneration zone or vessel diagrammatically it is to be understood that in fluid operations the regeneration will be carried out in a manner similar to that described above in connection with the reaction vessel 38. That is, the particles undergoing regeneration are maintained as a dense fluidized mixture with a dilute or dispersed phase superimposed thereabove. The hot regenerated catalyst particles are withdrawn from the base of the regenerator and returned to line 44 for introduction into the reaction vessel 38. Regeneration gases pass overhead through a separating means for separating entrained catalyst particles from the hot regeneration gases. The heat contained in the hot regeneration gases may be recovered in a waste heat boiler or other heat exchange system or apparatus.

Returning now to the second fractionating tower 68 the vaporous reaction products are fractionated to separate condensate oil which is withdrawn through line 92 from the bottom of the tower. A gas oil is withdrawn from trap-out tray 94 arranged above the inlet line 66 to the tower 68 and passes through line 96 to storage.

The hot vaporous reaction products on being introduced into the bottom of the second fractionating tower 68 are cooled and higher boiling constituents are condensed. These vaporous reaction products contain some entrained catalyst particles and these particles are recovered in the condensate oil as a slurry. The catalyst particles may be recovered from the condensate oil by filtering, settling or other separating operations.

The vapors pass overhead from the tower 68 through line 98 and are passed through condenser 102 to condense normally liquid hydrocarbons containing gasoline constituents. The cooled mixture is introduced into separator 104 for separating normally gaseous hydrocarbons which are withdrawn overhead through valved line 106. The normally liquid hydrocarbons comprising high antiknock gasoline are withdrawn from the bottom of separator 104 through line 108 and passed to storage. The gasoline is preferably further treated with sulfuric acid or clay to improve the quality of the gasoline. As these finishing treatments are old in the art it is not believed necessary to further describe them.

At least a portion of the liquid hydrocarbons withdrawn through line 108 is passed through line 112 by pump 114 into the upper portion of the second fractionation tower 68 as reflux liquid. Instead of using the reflux liquid cooling means may be provided in the upper portion of the tower 68.

Returning now to the higher boiling fraction which is withdrawn from the first fractionating tower 18 through line 14 the fraction may be partly preheated and then mixed with hot regenerated catalyst from line 116, a sufficient amount of catalyst being used to vaporize the oil and raise it to cracking temperature. According to my invention the fraction withdrawn through line 14 has an average boiling point above about 800° F. and for cracking this higher boiling stock I use a natural cracking catalyst such as powdered acid treated bentonite clay. I have found that, as high or higher octane gasoline is produced when cracking the higher boiling stock with a cheap natural clay catalyst than when cracking the same stock with the more expensive synthetically prepared silica alumina gel catalyst.

The mixture of the higher boiling fraction and the clay catalyst is passed through line 118 and into conical inlet member 122 provided with a perforated grid member 124 arranged in the bottom portion of the second reaction vessel 126. The powdered clay catalyst has about the same particle size distribution as the synthetic catalyst above described in the first cracking step. The velocity of the upflowing vapors in the second reaction vessel 126 is selected to maintain a dense fluidized bed or mixture 128 of catalyst particles having a level indicated at 132. The velocity of the upflowing vapors and the density of the bed or mixture 128 is substantially the same as that described above in connection with the first reaction vessel 38.

Above the dense bed or mixture is superimposed a dilute or disperse phase 134. The vaporous reaction products passing upwardly are introduced into separating means 136 through inlet 138 for separating entrained catalyst particles from the vapors. The separated particles accumulate in the separating means 136 and are returned through dip leg 142 to the dense bed or mixture 128. The separated vapors pass overhead through line 144 and may be passed through valved line 146 to the second fractionating tower 68 above described or they may be passed through valved line 148 to the bottom portion of a third fractionating tower 152 presently to be described in greater detail.

Similar to the operation described in connection with reaction vessel 38 the spent or partly deactivated catalyst particles are withdrawn 78 from the bottom portion of the spent reaction

vessel 126 and passed into the annular stripping zone or section 154 into which stripping gas is introduced through lines 156. The catalyst particles in the bottom portion of the vessel 126 are maintained in a fluidized condition by the introduction of fluidizing gas through one or more lines 158.

The stripped catalyst particles are then introduced into the upper portion of a second standpipe 162 provided with one or more fluidizing lines 164 for maintaining the particles in a fluidized condition in the standpipe 162. The fluidized mixture 128 and the fluidized mixture in the standpipe 162 produced a hydrostatic pressure at the base of the standpipe 162 which is used for passing the catalyst particles through the regeneration system. The spent catalyst particles pass through the control valve 166 and are mixed with a regenerating gas introduced through line 168 to form a less dense mixture or suspension which is passed to a second regeneration zone or vessel diagrammatically shown at 172. The hot regenerated catalyst particles are withdrawn and passed through line 116 for introduction into the second reaction vessel 126 and hot regeneration gases are withdrawn and passed through line 174.

As above pointed out in connection with the regeneration zone 86 the regeneration zone or vessel 172 may comprise a vessel similar to reaction vessels 38 and 126. That is, the catalyst particles undergoing regeneration are maintained as a dense fluidized mixture having a level with a dilute suspension superimposed thereabove. The regeneration gases pass overhead from the regeneration zone and are passed through a separating means to rerecover entrained catalyst particles from the regeneration gases. Heat may be recovered from the hot regeneration gases as above pointed out in the discussion of the first regeneration zone 86.

The hot regenerated catalyst particles are preferably withdrawn from the bottom portion of the regeneration zone as a dense fluidized mixture. In both regeneration steps stripping gas may be used for removing oxygen or other oxidizing gases from the regenerated particles.

Returning now to the third fractionating tower 152 the reaction products from the second reaction zone or vessel 126 are fractionated to separate a condensate oil which is withdrawn from the bottom of the tower 152 through line

176. This condensate oil contains catalyst particles which were entrained with the vapors and the particles may be recovered from the slurry by settling, filtering, etc. The gas oil is withdrawn from trap-out tray 178 through line 182.

The vapors pass overhead, pass through line 184, through condenser 186 and into separator 188. The gases are withdrawn overhead through line 192 and the normally liquid hydrocarbons containing high anti-knock gasoline are withdrawn through line 194. At least part of the gasoline-containing fraction withdrawn through line 194 is preferably blended with at least part of the gasoline fraction withdrawn through line 108 from the second fractionating tower 68. If desired, at least part of the virgin gasoline withdrawn through line 28 from the first tower 10 may also be blended with the mixture of the gasoline fractions just described.

20 To provide reflux for the third fractionating tower 152 at least a portion of the liquid hydrocarbons from line 194 is passed through line 196 by pump 198 into the upper portion of the tower. Instead of using reflux liquid, cooling means may be provided in the upper portion of the fractionating tower 152.

30 In the catalytic cracking in the second reaction vessel 126 the temperature may range from about 750° F. to 1050° F. and preferably about 925° F. to 1000° F. in the catalytic cracking step to form high anti-knock gasoline.

35 From cracking data I have noted that the octane number of the gasoline drops off precipitously when the feed stock average boiling point is raised from about 700° F. to about 800° F. when using the synthetic catalyst and that with a feed stock average boiling point above about 800° F., the octane number continues to drop off at a very moderate rate. Using acid treated bentonite clay as the catalyst and when the feed stock average boiling range is below about 800° F. or 850° F., the initial octane number of the gasoline is not as high as the octane number of the gasoline produced on a similar stock as above described using the synthetic catalyst, but the octane number of the gasoline does not fall off nearly as fast when the average boiling point of the feed stock is above about 800° F. or 850° F.

40 The following Table I lists the octane numbers produced when cracking various petroleum oils of different average boiling points.

Table I

¹ Conversion of the portion of the feed stock above its 20% distillation temperature to lower boiling products and coke.

² Synthetic catalyst is synthetically prepared silica alumina gel catalyst.

³ Natural catalyst is acid treated bentonite clay catalyst.

The following comments are offered concerning the data in Table I, which lists the octane numbers produced when cracking various petroleum oils of different average boiling points.

Operations numbered 2 and 3, 8 and 9 illustrate the effect of changing the conversion level only. Operations 3, 5 and 6 show that when using the synthetic catalyst, the octane number stays about the same, provided the boiling level is above 800° F. Operations 7, 10, 13 and 14 show that operating temperature affects the octane number. Because of this, Operations 7 and 13 would show slightly lower (about 0.5-1.0) octane number if they are carried out at 975° F. reactor temperature.

A comparison of the data in Operations 1-10 will show the sharp break in octane number obtained at about 800° F. average boiling point for synthetic catalyst. Operations 11-15 show no such trend with natural catalyst.

A comparison of Operations 2, 3, 5 and 6 with Operation 15 shows that the natural catalyst produces about as high an octane number as the synthetic catalyst on high boiling petroleum oils.

A comparison of Operations 7 and 13, or a comparison of Operations 10 and 14 shows that significantly higher octane numbers are obtained with the synthetic catalyst on low boiling petroleum oils. Operation 1 shows an intermediate boiling gas oil on synthetic catalyst which shows an intermediate octane number.

As a concrete example the following is given to show how the octane number of gasoline produced by catalytic cracking may be increased. In the first operation, using synthetic silica alumina catalyst, the gas oil had a boiling range (80%—20% point) of 775° F. to 930° F. with an average boiling point of 852° F. The catalyst to oil ratio was about 10. The temperature during the cracking was about 975° F. About 50% by volume of the feed of gasoline having a final boiling point of 400° F. was obtained and this gasoline had a CFRR octane number of 95.1.

In another example, using acid activated bentonite clay catalyst, the following is given. In this operation the gas oil had a boiling range (80%—20% point) of 705° F. to 1050° F. with an average boiling point of 879° F. The catalyst to oil ratio was about 4. The temperature during the cracking was about 971° F. About 53% by volume of the feed of gasoline having a final boiling point of 400° F. was obtained and this gasoline had a CFRR octane number of 94.9.

was about 167° F. The catalyst to oil ratio was about 9 and the temperature during the cracking was about 975° F. The amount of gasoline produced was about 42% by volume of the feed and the gasoline had a CFRR octane number of 98.9.

In another operation, using the same type of feed stock as described in the previous example, and using acid treated bentonite clay catalyst, the gas oil was carefully fractionated so that the 10 average boiling point was about 673° F. The boiling range (80%—20% point) of this feed stock was about 246° F. The catalyst to oil ratio was about 6 and the temperature during the cracking was about 975° F. The amount of gasoline produced was about 45% by volume of the feed and the gasoline had a CFRR octane number of 96.4.

In a third operation the feed stock was a similar type hydrocarbon oil and contained the higher boiling constituents. The catalyst used was synthetic silica alumina gel catalyst. The higher 20 boiling fraction had an average boiling point of about 803° F. and a boiling range of about 227° F.

The catalyst to oil ratio was about 6 and the temperature of cracking was about 975° F. The 25 amount of gasoline obtained was 46% by volume and the gasoline had a CFRR octane number of 97.0.

In another operation the feed stock was a similar type hydrocarbon oil and contained the 30 higher boiling constituents but the catalyst used was acid treated bentonite clay catalyst. The higher boiling fraction had an average boiling point of about 777° F. and a boiling range of about 342° F.

The catalyst to oil ratio was about 3 and the temperature of cracking was about 930° F. The amount of gasoline obtained was 51% by volume and the gasoline had a CFRR octane number of 95.2.

From the above operations it will be apparent that it is not as economical to crack high boiling gas oils with the more expensive synthetic catalyst when it is desired to make high octane gasoline.

In a more specific example, an East Texas hydrocarbon oil having a boiling range of about 430° F. to 1200° F. is fractionated into a 430° F. to 800° F. cut, which represents about 64% of the oil and an 800° F. to 1200° F. cut, which represents about 36% of the oil.

The separate cuts or fractions are catalytically cracked at 950° F. and at 60% conversion with different catalysts as follows:

	Stock	Catalyst ¹ Octane No.	Yield, Per cent	Catalyst ² Octane No.	Yield, Per cent
1	430-800° F.	97.1	37.3	94.8	45.8
2	800-1200° F.	92.1	49.0	92.6	58.8
3	430-1200° F.	95.3	41.5	98.9	60.4
4	Blend of Octane of 430-800° F. with synthetic catalyst and Octane of 800-1200° F. with clay catalyst to give octane number.		95.4 with yield of 44.8%		

¹ Synthetic silica alumina catalyst.

² Acid activated bentonite clay catalyst.

³ Calculated Blend of 1 and 2.

⁴ Calculated Blend of 1 and 2.

In another example or operation the same type feed stock was used as above described in connection with the first operation but the catalyst used was synthetic silica alumina gel catalyst and the gas oil was carefully fractionated so that the average boiling point was about 679° F. The boiling range (80%—20% point) of this feed stock

70 From the above it will be apparent that using synthetic catalyst on the 430-800° F. fraction results in higher octane and smaller yields for gasoline than with the clay catalyst but that a slightly higher octane number gasoline and higher yield of gasoline are obtained when using clay catalyst on the 800-1200° F. fraction than when us-

ing the synthetic catalyst. Also, using the blend of the octane number of the fractions cracked with separate catalysts, the blend of octanes will be 95.4 and the yield 44.8%, which shows that if the gasolines from the cracking steps are blended, a higher percentage of a slightly higher octane number gasoline is obtained.

From the above data it will be seen that improved octane numbers are obtained by selecting the gas oil fraction to be catalytically cracked in the presence of a synthetic cracking catalyst. In such a case, the gas oil fraction is selected to have an average boiling point below about 800° F. As the octane number decreases more rapidly on the higher boiling stock when using synthetic catalyst than when using the clay catalyst, it is also within my invention to crack a lower boiling gas oil stock having an average boiling point below about 800° F. with synthetic catalyst and cracking the higher boiling gas oil having an average boiling point above about 800° F. with clay catalyst to produce gasoline having as high or a higher octane number than that produced when cracking a higher boiling gas oil stock with the expensive synthetic catalyst alone.

While I have disclosed my invention in connection with powdered catalyst in a bottom draw-off unit, it is to be understood that my invention may also be used with powdered catalyst in an upflow unit and with fixed bed catalyst units where the catalyst remains in a vessel and is regenerated in the same vessel after being used for some time. My invention may also be used with the moving bed type of operation in which the catalyst particles are in the form of pellets or rods and are mechanically moved through the reaction vessel and then through a separate regeneration vessel before being returned to the reaction vessel.

While I have shown one form of apparatus for carrying out my invention, it is to be understood that various changes and modifications may be made without departing from the spirit of my invention.

I claim:

1. A process for catalytic cracking of hydrocarbons to produce higher yields of high octane gasoline which comprises separating a wide boiling range hydrocarbon oil into a low boiling fraction having an average boiling point below about 800° F. (average boiling point being the temperature at which 80% of the stock boils off plus the temperature at which 20% of the stock boils off with the total divided by 2) and a higher boiling fraction having an average boiling point above about 800° F., passing the low boiling fraction having an average boiling point below about 800° F. in the vapor phase through a first cracking zone containing powdered synthetic silica alumina catalyst with a catalyst to oil ratio by weight of from 1 to 40 and maintained at a temperature of about 975° F. to form high octane number gasoline having an octane number of at least 97 (CFR-Research Method), separating high octane gasoline from the cracked products, mix-

ing a sufficient amount of powdered hot regenerated acid treated bentonite clay catalyst with said higher boiling fraction to vaporize the higher boiling fraction and raise it to cracking temperature, passing the vaporized higher boiling fraction and catalyst through a second cracking zone maintained at a temperature of about 975° F. to form high octane number gasoline having an octane number of about 95 (CFR-Research Method), separating high octane gasoline from the last-mentioned cracking step and blending high octane gasoline from the first cracking step with high octane gasoline from the second cracking step to produce a higher yield of 95 octane number gasoline than would be obtained by using a single catalyst.

2. A process for catalytic cracking of hydrocarbons which comprises separating a wide boiling range hydrocarbon oil into a low boiling fraction having an average boiling point below about 800° F. (average boiling point being the temperature at which 80% of the stock boils off plus the temperature at which 20% of the stock boils off with the total divided by 2) and a higher boiling fraction having an average boiling point above about 800° F., passing the low boiling fraction having an average boiling point below about 800° F. in the vapor phase through a first cracking zone containing powdered synthetic silica alumina catalyst with a catalyst to oil ratio by weight of from 1 to 40 and maintained at a temperature of about 975° F. to form high octane number gasoline, separating high octane gasoline from the cracked products, mixing a sufficient amount of powdered hot regenerated acid treated bentonite clay catalyst with said higher boiling fraction to vaporize the higher boiling fraction and raise it to cracking temperature, passing the vaporized higher boiling fraction and catalyst through a second cracking zone maintained at a temperature of about 975° F. to form gasoline having at least as high an octane number as would be obtained by cracking the higher boiling stock with the silica alumina catalyst but producing a higher yield of such gasoline, separating high octane gasoline from the last-mentioned cracking step and blending high octane gasoline from the first cracking step with high octane gasoline from the second cracking step to produce a higher yield of high octane gasoline than would be obtained if using the same type of catalyst for both fractions of feed stock.

FORREST H. BLANDING.
